UNITED STATES PATENT OFFICE

CHARLES W. DUNCAN, OF SAUSALITO, CALIFORNIA

BUILDING CONSTRUCTION

Application filed October 7, 1929. Serial No. 397,852.

This invention relates to improvements in building construction, and more particularly to the material and the method of combining the various products and materials in the 5 walls of buildings.

I am aware that building walls have been constructed of reinforced monolithic concrete; that cementitious slabs have been erected in spaced relation, and the space filled 10 with concrete; that hollow tiles have been erected and subsequently filled with concrete, and that cellular blocks have been built into 15 walls.

But so far as I am aware I am the first 15 to build two interspaced walls of cellular blocks, held in spaced relation by invisible bridge clips, with oblique reinforcing rods arranged in said space prior to casting a monolithic wall within said composite wall, as 20 will be hereinafter more fully described.

Among the objects of the invention is to 25 economically provide a rigid, reinforced concrete, monolithic wall, cast in place without the use of removable molds.

Another object is to provide such a wall 30 wherein transverse capillary attraction for moisture is absent.

A further object is to provide such a wall 35 with the maximum of thermal insulation with the minimum of cross section. Other objects and advantages will appear as this description progresses.

In this specification and the accompanying 40 drawing the invention will be disclosed in its preferred form. But it is to be understood that it is not limited to that form, because it may be embodied in other forms. It is also to be understood that in and by the 45 claims following the description it is desired to cover the invention in whatsoever form it may be embodied.

In the one sheet of drawing:

Figure 1 is a fragmentary front elevation 45 of a wall constructed in accordance with this invention, and showing an edge view of the side wall.

Figure 2 is a plan view from above of the same.

Figure 3 is a detail in elevation of the

assembling clip for interspacing and tying the surface blocks together.

Figure 4 is a top view of the same.

In detail the construction illustrated in the drawing comprises blocks or slabs of 55 cellular plastic or cement. These slabs 1 are cast in molds of the desired size. A very convenient size slab for small residences or bungalows is 8 x 16 inches and two inches 60 thick.

These slabs are preferably formed of "bubble stone". This is composed of ordinary Portland cement or other suitable cementitious plastic to which has been added a suitable chemical that will cause effervescence or bubbling prior to the first setting 65 reaction. The resultant mass is an aerated structure, resembling pumice. It has high thermal insulating qualities, low specific 70 gravity and the necessary strength for the purpose. This strength can be increased by reducing the effervescent reaction to increase the specific gravity of the resultant slab.

It can be sawed, chipped and hewn where 75 fitting is necessary, and can be nailed into without splitting or fracturing. It forms a perfect key surface for the application of any form of plaster, stucco, paint, and the conventional interior and exterior finishes 80 or tint may be added to the batch mix for natural finish.

It is as fire resisting as the material of 85 which it is composed, and has a strong chemical and mechanical affinity for Portland cement, which latter advantage will be described later. Its bubble or cellular texture renders it practically impervious to moisture; that is, ordinary surface moisture 90 will not penetrate through it as is the case of an equal cross section of brick, cement, and similar solid capillary structures.

These slabs can be very economically 95 formed by casting a batch in a large shallow mold and cutting the mass into slabs of the desired dimensions with a blade while it is still plastic and before it sets hard. Greater accuracy, where this is a consideration, is gained by casting each slab in a snap 100

mold for the preliminary set, before exposed curing.

In building a wall, in accordance with this invention, it is desirable to have the top of the foundation 2, level and flat. Two parallel rows of slabs on edge are stood upright on the top of the foundation to form the first course. These are held firmly in spaced relation by the assembling clips.

10 A very effective form of clip is shown in Figure 3. It comprises the cross bar 4, of the proper length, having the transverse spacers 5 and dowels 6 welded thereto. The spacers are uniformly set apart a distance 15 equal to the distance between the opposed faces of the slabs. The dowels are set apart a distance equal to the distance between the centers of the thicknesses of the slabs. These clips are composed of ordinary steel wire 20 about one eighth of an inch in diameter.

Resistance to penetration is so low in the slabs that the dowels can be pushed into the slabs up to the cross bar 4 by hand. In the harder slabs they can be hammered in.

25 The succeeding courses of slabs are set against the upstanding spacers 5—5 and pushed down until the dowels 6 penetrate them and they rest upon the lower course.

This operation is repeated until the desired 30 wall height is reached. This height is partly determined by the space between the slabs. Consideration must be given to the fluidity of the concrete to be poured between the interspaced inner and outer slabs 1, 1'.

35 In placing the slabs they are laid in break joint relation and interlocked at the corners, in accordance with the practice of brick laying and masonry. This double or composite wall has sufficient lateral stability aided by 40 the cross clips to maintain itself when built into architectural structures.

The reinforcing bars 7 are introduced between the slabs 1, 1' at intervals. The short lengths at the corners are placed as the wall 45 is built up. The longer lengths can be placed after the wall has reached the desired height. These bars are preferably arranged in criss-cross oblique formation to give better bracing effect.

50 One advantage of the wire form of clip is that it presents no obstruction to the entrance of the bars 7, which are guided by and supported by the clips that they contact. These rods should be concentrated at the center of the space.

Suitable door and window casings are introduced into the wall as it is laid, in accordance with conventional practice. Thus assembled, it is ready to "pour".

The pouring consists of introducing fluid concrete into the space between the slabs 1, 1', in the conventional manner.

55 Since it is desirable to produce a wall as thin as practicable, the concrete core 8 should

be a rich mixture, sufficiently wet to flow freely and form a dense core.

The walls 1, 1' form a perfect form into which to cast the concrete core 8. The cellulated surface of the slabs causes the concrete to weld and key itself firmly thereto and transform the composite wall into a homogeneous reinforced monolithic whole.

60 The cellulated surfaces between the superimposed slabs prevent even thin grout from flowing out between the slabs; neither do the slabs absorb or suck the water from the grout. The result is a perfect curing chamber for the concrete core 8, protected from extremes of heat or cold and too rapid evaporation.

65 The joists 9 of succeeding floors can be laid atop the inner slabs 1, with their ends overhanging the space adjacent the outer slabs 1', so that the pouring of the core 8 will enclose the ends of the joists and firmly embed them therein. The inner slabs 1 are formed or trimmed to fit snugly between the joists. For concrete floors, the reinforcement bars thereof can be similarly anchored in the core 8.

70 Ordinary skilled labor can be used in the practice of this invention. Inequalities in the walls can be hewn away or rubbed even with the plane with a coarse stone. The slabs are a perfect key base for the application of plaster or any other desired plastic treatment or paint washes.

75 Such walls are cheap, strong, non-conducting to temperature, sound and moisture, and proof against earthquake, with other incidental advantages.

80 For buildings of several stories the cross section of the core can be increased and the strength of the slabs raised by reducing the effervescent medium and increasing the density proportionate to the load stress upon the walls of the lower stories and foundations.

85 Having thus described this invention what is claimed and desired to be secured by Letters Patent is:

1. A building structure comprising inner and outer interspaced walls of non-capillary aerated cementitious material, and a cementitious filler cast between said walls to form a substantially homogeneous monolithic whole.

100 2. A building structure comprising inner and outer interspaced walls, composed of superimposed courses of non-capillary aerated cementitious slabs; cross clips consisting of horizontal cross bars and vertical dowels joining said walls; diagonally disposed reinforcing bars resting on said cross clips in the space between said walls; and a cementitious filler cast between said walls and adapted to

105 adhere to the surfaces of said slabs to form a substantially homogeneous monolithic whole.

110 In testimony whereof I have hereunto set my hand this 1st day of October A. D. 1929.
